UNITED STATES PATENT OFFICE.

RODNEY G. RICHARDSON, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed February 14, 1916, Serial No. 78,161. Renewed June 26, 1920. Serial No. 392,042.

To all whom it may concern:

Be it known that I, RODNEY G. RICHARDSON, a citizen of the United States of America, and a resident of Chicago, county of Cook, and State of Illinois, have invented certain new and useful Improvements in Automatic Telephone Systems, of which the following is a specification.

My invention relates to automatic telephone systems and as to its principal features relates more particularly to such systems as employ so called finder switches for connecting a calling line with a selector or connector switch.

In systems of the above general character the lines are divided into groups, and there is provided for each group of lines a sufficient number of finder switches to handle the maximum number of originating calls from that group. Each finder may be directly connected to a selector or connector switch, depending on the size of the system, through the medium of which a calling line, when located by a finder switch, may be extended into connection with a called line.

I am aware that a great many systems employing finder switches operating on the general plan outlined above have been devised before this, but to the best of my present knowledge these systems are all open to the objection that some of the lines require a very considerable movement of the movable contacts of a finder switch for their location. These lines may not always be the same ones, for in some systems the movable contacts or wipers of the finders have no normal position; but whatever the position of the wipers when their movement is started, they must, to reach certain of the lines, move a considerable and almost prohibitive distance.

This difficulty cannot be absolutely and in all cases removed, for should there be but one idle finder switch when a call is initiated, this finder must advance its wipers to locate the calling line, no matter what its position be relative to the starting position of the finder wipers. It is possible, however, to reduce the movement required to locate a calling line sufficiently for all practical purposes by providing that the finder switch wipers shall have no normal position, i. e., they shall remain on the contacts of the line last served; by providing fur-

ther that if a calling line already has in engagement with its contacts the wipers of a finder switch, that this finder shall be used; and by providing finally that if a calling line has no finder switch wipers in engagement with its contacts and there is more than one finder idle that the finder which requires the least movement of its wipers to reach the calling line will be started. In other words, whenever there is more than one finder in a group idle, a calling line will start that idle finder whose wipers, in so far as the possibility of their connecting with the calling line is concerned, happen to be closest to the contacts of that line.

The principal object of my invention, then, is to provide in a system of the above general character, a suitable and efficient method by which a calling line will be served by that one of a plurality of idle finders whose wipers require the least movement to reach its contacts.

A further object is to provide in connection with the above, means whereby finder switches in the same group may be started in rapid succession by successively calling lines.

Further objects relate to improvement in circuit arrangement whereby these features are incorporated in a practical and efficient system.

To accomplish the foregoing and other useful ends my invention comprises means which will be hereinafter set forth and claimed, reference being had to the accompanying drawings.

In the drawings Figures 1 and 2, taken in order with the lines at the ends thereof in alignment, represent diagrammatically a complete circuit connection between a calling substation A and a called substation A', in a system embodying the principles of my invention. The said connection has been established through the medium of the finder switch C, the selector switch D, and the connector switch E. In Figure 3, I have shown a top view of the mechanism of the finder switch C, while Figure 4 represents a cross-section of Figure 3 on the line a, b. In Figure 5, I have shown the starting connections and a portion of the banks of three finder switches belonging to the same group. Figure 6 is a schematic representation of one of the circuits shown in Figure 5.

The substation A (Fig. 1) may be of the

General type of substation shown in British patent to T. G. Martin No. 1419 of 1910. As herein represented it consists of the receiver 2, transmitter 3, receiver hook 4, ringer 5, and condenser 6. Being an automatic substation it is also provided with a pair of impulse springs 8 and 9 controlled by the impulse wheel 7, which in turn is controlled through the medium of a finger hole dial (not shown). The impulse springs and wheel as shown herein may be arranged in the manner shown in British patent to S. G. S. Dicker 29,654 of 1910.

The line conductors 11 and 12 of the substation A have allotted to them at the exchange the line and cut-off relays 21 and 20; a set of multiple bank contacts in the bank of each finder switch, one of these sets being indicated by reference characters 35—39, inclusive; a pair of contact springs 45 and 46 associated with each set of finder bank contacts; and a set of multiple bank contacts (not shown) in the bank of each connector, such as connector E (Fig. 2), which has access to the group of lines of which the line of substation A is one. The normal conductors 13, 14, and 15 extend to the latter sets of bank contacts. The functions of the line and cut-off relays are very similar to the usual functions of these relays in other well known systems, although the line relay 21 in my system is somewhat different in operation as will appear more fully hereinafter. The bank contacts 37, 38, and 39 in the bank of finder switch C are multiplied to corresponding contacts in the banks of all other finder switches in the group; each line of the group of which the line of substation A is one, of course, being multiplied through the banks of these finders in the same manner. The bank contacts 35 and 36, however, and similar contacts of other lines of the group, are not multiplied straight to corresponding contacts in the banks of other finders, as are contacts 37, 38, and 39, but are connected in a peculiar loop circuit which will be fully explained hereinafter.

The finder switch C may be briefly described as a rotary switch whose wipers have a movement in one direction only and have no normal position. Referring to Figures 3 and 4, the frame of the switch is formed of a circular base plate 200 and a ring shaped upper mounting plate 201, the two being separated the proper distance and rigidly connected by posts 202, 203, 204, and 205. Supported on bearings in the upper and lower frame plates, is a shaft 206 to which is rigidly secured an arm 207, a ratchet wheel 210, and five sets of wipers insulated from each other, one set being indicated by reference character 215. A magnet 208, attached to base plate 200 by means of the heel piece 209, is adapted, when energized, to rotate the shaft 206 through the

medium of armature 211, pawl 212, and ratchet wheel 210. The spring 212 tends to hold the pawl 212 constantly in engagement with ratchet wheel 210. The dog 214, which also engages the ratchet wheel 210 serves to prevent backward rotation of the shaft 206.

The various sets of bank contacts are preferably arranged in a complete circle, and there are shown in Fig. 3 fifty of these sets, by which it appears that there will be fifty lines in the group to which the finder switch C has access. The exact number, however, is immaterial, it being easily possible and perhaps advisable to increase the number of lines in each group to one hundred. It is understood that the manner in which the finder switch banks and wipers are shown in Figure 1 is purely diagrammatic, the actual construction of these parts being as shown in Fig. 4. In the latter drawing the bank contacts 35—39, inclusive, correspond to the same numbered contacts in Figure 1 and are individual to a certain line. The bank contacts 40—44, inclusive, correspond to the wipers 40—44, inclusive, in Figure 1, and are preferably complete circular strips extending around the entire circumference of the bank. Attached to the strips 40—44, inclusive, are conductors which extend to the relays of the switch, shown at C (Fig. 1). It is evident that at all times a certain set of contacts such as contacts 35—39, inclusive, will be connected to the common strips 40—44, inclusive, by means of the five sets of wipers.

As before mentioned, each set of bank contacts has associated with it a pair of normally closed contact springs, one of these pairs being indicated by reference characters 45 and 46 (Figs. 1 and 4). The arm 207 carries an insulating piece 47 which is adapted to separate the pair of contact springs between which it happens to be resting. Or, in other words, no matter what set of bank contacts the wipers are resting on, the pair of contact springs associated with that set will be separated by the insulating piece 47.

Referring now to Fig. 5, I have shown diagrammatically therein six sets of bank contacts in each of three finder switch banks, together with six starting wires and their connections in the banks. The six sets of contacts immediately adjacent to the line and cut off relays at the left of the drawing are located in the bank of the first finder of the group, finder switch C; the six sets of contacts at the extreme right of the drawing are located in the bank of the last finder of the group (not shown); while the other six sets of bank contacts are located in the bank of an intermediate finder. It is to be understood that in actual practice there may be more than three finder switches in a group and that each finder, as already explained, will have fifty or even one hundred sets of

contacts instead of six, but it is thought that sufficient contact sets and finder banks are represented to show what is intended. Counting from the top the three sets of 5 finder switch wipers are shown resting, respectively on the third, second and fifth sets of contacts in their respective banks. The wipers when in motion move in an upward direction, as represented in Fig. 5.

10 The starting wires are indicated by reference characters 230-235, inclusive. There are as many separate starting wires as there are lines in the group and each starting wire extends from the line relay of the line with 15 which it is associated to the starting wire contact of that line in the bank of the first finder switch of the group. For example, starting wire 232 extends from a contact on the line relay of No. 3 line to bank contact 238, in the third set of contacts in the bank of the first finder switch. In the same manner, starting wire 233 extends from a contact on the line relay of line No. 4 to bank contact 239 in the fourth set of contacts in 20 the bank of the first finder switch. Also, by referring to Figure 1, the starting wire 231 associated with the line of substation A is seen extending from contact 29 on line relay 21 to bank contact 36 in the bank of finder 25 switch C, which is assumed to be the first switch of the group.

From the foregoing it will be clear that each line of a group is provided with an individual starting wire extending from its 35 line relay to the bank of the first finder switch in the group. I will now explain how the various starting wires are connected in the banks of the remaining finder switches. Considering the starting wire 230, 40 which is the one associated with line No. 1 (not shown), a complete series circuit which includes every set of contact springs such as 45 and 46 (Figs. 1 and 4) in every finder switch may be traced as follows: starting wire 230, bank contact 236, contact springs 270 and 271, bank contact 242, bank contact 248, contact springs 272 and 273, bank contact 250, bank contact 252, contact springs 274 and 275, bank contact 253, wire 45 junction 300, and starting wire 231 to bank junction 301; thence by way of the second 50 pairs of contact springs of the three finders in series to wire junction 302; thence by way of the third pairs of contact springs of the three finders in series to wire junction 303; thence by way of the fourth pairs of contact springs of the three finders in series to wire junction 304; and thence by way of the fifth pairs of contact springs of the three finders in series and the dotted conductor 310 to wire junction 305, 55 where it joins starting wire 230 again and

forms a complete loop. Conductor 310 is shown dotted to indicate that it passes through other pairs of contact springs not shown before returning to wire junction 305. The individual starting wires may be considered as taps taken off from the main loop circuit at the first finder switch bank. It will be observed that the above described loop circuit is divided into as many sections as there are finder switches by means of the 70 insulating pieces 290, 291, and 292 which correspond to insulating piece 47 (Figs. 1 and 4). The finder switches may be considered as each standing, when idle, at the division point between two adjacent sections, 75 each finder being adapted to serve those lines whose starting wires are tapped on to the section immediately in front of that finder. There may be but one starting wire attached to a given section or there may be 80 many more, depending obviously on the position of the other finders.

For the sake of additional clearness I have shown in Figure 6, the loop circuit and six starting wires of Fig. 5, together with a 90 starting relay in each of the three finders, all unnecessary details being omitted. When taken in connection with the foregoing description of Fig. 5, it is thought that Fig. 6 will be understood without difficulty. 95

The relays shown at H (Fig. 5) are common to a group of finder switches and may be termed emergency starting and stopping relays. Their functions will be more fully explained hereinafter. 100

Returning now to Figure 1, the finder switch C is connected directly with the selector switch D which may be of the general type of selector switch disclosed in U. S. Letters Patent No. 815,321, granted March 13, 1906, to Keith, Erickson and Erickson; being, however, of the particular type disclosed in British patent to the Automatic Telephone Manufacturing Company, No. 2543 of 1914. Among other details the selector D comprises a bank of contacts arranged in horizontal rows or levels, which contacts are adapted to be engaged by a set of wipers 120, 121, and 122, carried upon a shaft (not shown) which has a vertical movement controlled by a vertical magnet 109, and a rotary movement controlled by a rotary magnet 110. The operation of the various parts of the switch is controlled through the medium of the double wound line relay 100. Means for permitting the switch to be restored to normal position is provided in the release magnet 105 which, upon energizing, withdraws the retaining pawls from the shaft. The contacts 112 and 113 make against their respective springs only when the shaft has been raised one or more steps from its normal position. The relays 104 and 106 are slow acting, i. e., each of these relays is able to retain its armature 115 120 125 130

for an instant after its energizing circuit is broken.

As is well known, a selector of the type shown herein may be given access to a number of groups of connector switches, which connectors in turn have access to groups of subscribers' lines for the purpose of completing connections thereto. One of these connectors is shown at E, Fig. 2. The connector E may be of the general type of connector switch disclosed in U. S. Letters Patent No. 815,176 granted March 13, 1906, to Keith, Erickson and Erickson; being, however, of the particular type disclosed in British patent to the Automatic Telephone Manufacturing Company, No. 2270 of 1914. Among other details the connector E comprises a bank of contacts arranged in horizontal rows or levels, which contacts are adapted to be engaged by a set of wipers 160, 161, and 162, carried upon a shaft (not shown) which has a vertical movement controlled by the vertical magnet 143, and a rotary movement controlled by the rotary magnet 144. The usual side switch comprising the wipers 156, 157, 158 and 159 is controlled by the private magnet 147 in the well known manner. The operation of the various parts of the switch is controlled through the medium of the double wound line relay 140 which relay also serves to supply talking current to the calling line. A called line is furnished with talking current from the windings of the double wound answering bridge relay 150. The ringing relay 149 affords means for projecting ringing current over the called line to signal the called subscriber. Means for restoring the switch to normal position is provided in the release magnet 152, which, upon energizing, withdraws the retaining pawls from the shaft and restores the side switch wipers to their first position. The contacts 154 and 155 make contact with their respective springs only when the shaft has been raised one or more steps from its normal position. The relays 153 and 146 are slow acting.

The connector E has access through its wipers and bank contacts to a group of subscribers' stations one of which is shown at A'. The substation A' may be similar in all respects to substation A and is provided with similar individual line equipment.

For supplying current for operating and talking purposes I have shown a battery B having one terminal grounded. The battery B' shown in Fig. 5 may be the same battery or a different battery from that illustrated at B in Fig. 2. For supplying ringing current I have shown a generator R and for busy signaling purposes I have shown a busy signaling machine Q.

Having given a general description of the apparatus I will now proceed to describe the operation of a system embodying the

principles of my invention. For the purposes of this explanation it will be assumed that the subscriber at substation A (Fig. 1) desires to establish a connection with the subscriber at substation A' (Fig. 2). Inasmuch as a great deal of the automatic apparatus shown herein is old and well known in the art, having been fully described in the publications referred to, its operation will be described in a more or less general manner, the details being given only when they have to do in some way with the application of the principles of my invention.

Referring now to Fig. 1, the subscriber at substation A, upon removing his receiver to initiate the call, completes a circuit which includes a winding of line relay 21, individual starting wire 321, and a pair of starting relays in that finder switch whose wipers require the least movement in order to reach the contacts in its bank allotted to the line of substation A. Assuming that the wipers of finder switch C are already resting upon contacts individual to substation A, the above mentioned circuit may be traced as follows: ground at G², winding 55 of relay 54, winding of relay 53, contact 70, armature 69, contact 68, spring 67, wiper 41, bank contact 36, starting wire 321, contact 29, spring 30, contact 27, armature 26, line conductor 11, to and through substation A, line conductor 12, armature 24, contact 25, and winding 22 of line relay 21 to battery B. In response to current flow in the above path, relays 21, 53, and 54 attract their armatures. The armature of relay 21 is adjusted with a rather long stroke and the contact against spring 32 is made before spring 30 is separated from contact 29. As a result of the latter operation, which takes place near the end of the stroke, the original energizing circuit is broken, but not before relays 53 and 54 have fully attracted their armatures. Relay 21 is enabled to complete its stroke by reason of the new path to ground by way of common relay 90 closed by armature 28 and spring 30. A temporary locking circuit for relay 54 may now be traced as follows: ground at G², winding 55 of relay 54, contact 66, spring 63, wiper 42, bank contact 37, spring 32, armature 31, holding winding 23 of line relay 21, and winding of cut off relay 20 to battery B. The cut off relay 20, upon energizing, breaks the energizing circuit of winding 22 of line relay 21, but relay 21 retains its armature attracted by reason of its holding winding 23, now carrying current in series with the cut off relay winding.

An instant after the temporary locking circuit of relay 54 was established by the energization of relay 21, the slow acting relay 53 retracts its armature, thereby completing an energizing circuit for line switching relay 51 as follows: ground at G², armature 78, contact 80, armature 74, contact 75, contact 76, and winding 22 of line relay 21 to battery B.

holding winding 56 of relay 54, armature 81, contact 82, and winding of relay 51 to battery B. Relay 51, upon attracting its armature, brings about the following circuit changes. By bringing armature 64 into engagement with spring 63 and by separating the latter from contact 66, the temporary locking circuit of relay 54 by way of its winding 55 is broken and relay 54 remains energized by reason of its low resistance holding winding 56. By the substitution of winding 56 for winding 55, the test contact 37 and its multiples are brought sufficiently near to ground potential to make the line of substation A busy to other finder switches that may be started. Also, by reason of the low resistance of holding winding 23 of line relay 21, the conductor 15 and the multiple test contacts in the banks of connector switches to which it extends are brought sufficiently near to ground potential to make the line of substation A busy to those connector switches. As a further result of the energization of relay 51 the wiper 41 is disconnected from relay 53 and is connected directly to wiper 40 in an obvious manner. This is done for the purpose of maintaining the continuity of the loop starting circuit while finder switch C is busy. Finally, by bringing armatures 59 and 60 into engagement, respectively, with contacts 61 and 62, relay 51 extends the line conductors 11 and 12 to the double wound line relay 100 of the selector D. Two energizing circuits for relay 100 may now be traced, one of which extends over the following path: ground at G⁵, winding 103 of relay 100, contact springs 115 and 116, contact 61, armature 59, wiper 43, bank contact 38, conductor 16, line conductor 12, substation A, line conductor 11, conductor 17, bank contact 39, wiper 44, armature 60, contact 62, contact springs 117 and 118, and winding 102 of relay 100 to battery B. The second energizing circuit extends as follows: ground at G³, armature 78, contact 80, armature 74, contact 75, armature 60, contact 62, contact springs 117 and 118, and winding 102 of relay 100 to battery B. Ordinarily the latter circuit, which is in effect a short circuit of winding 103 and the substation A, could be dispensed with. Its purpose will appear later.

Upon attracting its armature, the line relay 100 completes an energizing circuit for the slow acting relay 104, which relay, upon energizing, prepares circuits for the vertical and rotary magnets 109 and 110 in the well known manner and also completes a holding circuit which may be traced over the following path: ground at G⁶ and contact springs 130 and 131 to armature 64, where the circuit divides, one branch extending by way of the winding of line switching relay 51 to battery B, and the other branch extending by way

of spring 63, wiper 42, bank contact 37, spring 32, armature 31, winding 23 of relay 21, and winding of cut off relay 20 to battery B. It will be observed that as soon as the above holding circuit is established the 70 winding 56 of relay 54 is short circuited. Upon deenergizing, relay 54 breaks the last described energizing circuit of line relay 100, thereby leaving the selector D under the control of the substation A. 75

The purpose of the auxiliary energizing circuit for line relay 100 may now be seen. Should the subscriber at substation A remove his receiver and replace it, in the interval between the pulling up of relay 21 80 and the pulling up of relay 104 of the selector, relay 54 would remain locked up by its winding 56, thereby maintaining the finder switch in a busy condition until the next call by substation A. The auxiliary 85 energizing circuit for line relay 100 is provided to obviate this possibility.

Before continuing with the operation of the selector D and connector E it will be well to consider the operation in the case 90 where no finder switch is resting upon the contacts of the calling line. We will assume that the finder switch C is idle and that its wipers happen to be nearer to the contacts of the line of substation A than the wipers of 95 any other finder. It follows then that the section of the starting loop to which starting wire 321 is tapped will terminate in the bank contact upon which wiper 41 is resting, as explained in connection with Fig. 5. 100

Upon the removal of the receiver at substation A an energizing circuit is completed as previously described for relays 21, 53, and 54, except that in this case the circuit includes a portion of the starting loop. 105 Relay 21, upon energizing, prepares a circuit for the cut-off relay 20 by bringing armature 31 into engagement with spring 32, breaks the original starting circuit by separating contact 29 and spring 30, and 110 locks itself by bringing armature 28 into engagement with spring 30, all as previously described. The instant spring 30 is separated from contact 29, relay 54 de-energizes but relay 53, being slow acting, 115 retains its armature for an instant thereby completing the following circuit: ground at G³, armature 78, contact 79, armature 76, contact 77, winding of relay 52, winding of rotary magnet 50, interrupter contact 120 springs 58, and common relay 91 to battery B. Relay 52, upon attracting its armature 72 completes the above circuit over a path which is independent of the relay 53, whereby the deenergization of this relay an 125 instant later is without effect.

As soon as the circuit just described is completed the rotary magnet 50 operates to vibrate its armature 211 by means of the interrupter contact springs 58, thereby ro- 130

tating the wipers 40-44, inclusive, in search of the contacts of the calling line. Relay 52, being slow acting, retains its armature although its circuit is broken at 5 each energization of magnet 50. During the rotation of the finder switch, wiper 41 is disconnected from relay 53 by the attraction of armature 69 of relay 52 and is connected at the same time to wiper 40 for the 10 purpose of maintaining the continuity of the starting loop.

When wiper 42 arrives at bank contact 37 an energizing circuit is completed for relay 54 and cut-off relay 20 over the following path: ground at G^2 , winding 55 of relay 54, contact 66, spring 63, wiper 42, bank contact 37, spring 32, armature 31, winding 23 of relay 21, and winding of cut-off relay 20 to battery B. The above 20 circuit is the same as one previously described and referred to as the temporary locking circuit of relay 54. Upon attracting its armature, relay 54 breaks the rotary magnet circuit by separating armature 78 25 and contact 79, thereby stopping the rotation and bringing the wipers 40-44, inclusive, to rest upon contacts 35-39, inclusive. From this point the operation is the same as described in the case where it 30 was assumed that the wipers of finder switch C were already resting upon the contacts of the line of substation A.

We may now return to the selector D and consider briefly its operation. In response to the manipulation of the dial at 35 substation A in accordance with the first digit of the desired number, the impulse wheel 7 interrupts the circuit of the line relay 100 a number of times in the well known manner. As a result of these interruptions the line relay 100 is deenergized a corresponding number of times, sending an impulse at each deenergization from ground at G^7 to the slow acting relay 106 40 and the vertical magnet 109 in series. The vertical magnet, in response to these impulses, steps up the shaft until the wipers stand opposite the horizontal level in which are located contacts which are terminals of the desired group of connectors. The relay 106, being slow acting, retains its armature during the series of impulses and closes 45 a circuit for the test relay 108 which latter relay prepares a circuit for the rotary magnet and locks itself to ground at G^6 . At the end of the series of impulses the relay 106 deenergizes, thereby closing a circuit for the rotary magnet 110, whereupon the wipers 120, 121, and 122 start rotating 50 in search of a trunk extending to an idle connector. As is well known, the rotary magnet interrupts its own circuit and also the locking circuit of the test relay at every energization, the contacts in the latter circuit, however, being short circuited by the

test wiper 121 while passing over busy or grounded contacts. As soon, therefore, as the test wiper reaches an ungrounded test contact the test relay falls back and opens the rotary magnet circuit, thereby bringing 70 the wipers to rest upon contacts which are terminals of a trunk leading to an idle connector switch, assumed in this case to be the connector E. As a further result of the deenergization of the test relay 108, a circuit is completed for the line switching relay 107, which relay, upon energizing, disconnects the extended line conductors 12 and 11 from the windings of the line relay 100 and further extends them by way of 80 wipers 120 and 122 and bank contacts 123 and 125, to the double wound line relay 140 of the connector E.

The line relay 140 thereupon energizes over the previously traced circuit through 85 substation A, and completes an energizing circuit for slow acting relay 153. Relay 153, upon energizing, prepares a circuit for the vertical and rotary magnets 143 and 144 and also completes a new holding circuit as follows: ground at G^9 , contact springs 170 and 171, bank contact 124, and wiper 121 to wire junction 132, where the circuit divides, one branch extending by way of contact springs 133 and 134 and 90 winding of line switching relay 107 to battery B, while the other branch extends by way of contact 112 and contact 111 to wire junction 135, where it joins the previously described holding circuit extending back 100 to the finder switch C.

The subscriber at substation A may now operate his dial in accordance with the second digit of the desired number, resulting in this case in deenergizations of the line 105 relay 140 of the connector E. At each deenergization the line relay 140 sends an impulse from ground at G^9 to the slow acting relay 146 and the vertical magnet 143 in series, side switch wiper 156 being in its first 110 position. The vertical magnet, in response to these impulses, steps up the shaft until the wipers stand opposite the horizontal level in which are located contacts which are terminals of the line of substation A'. The 115 relay 146 being slow acting, retains its armature during a series of impulses and maintains a circuit from ground at G^{10} to the private magnet 147. At the end of the series of impulses the relay 146 and the private magnet deenergize, the latter controlling the side switch wipers in the usual manner, to advance them to their second position.

The subscriber at substation A may now 125 operate his dial in accordance with the third and final digit of the desired number, resulting as before in deenergizations of the line relay 140. In this case, however, the line relay sends impulses to the slow acting 130

relay 146 and the rotary magnet 144, side switch wiper 156 being in its second position. The rotary magnet operates in response to these impulses to rotate the wipers 160, 161, and 162 until they rest, respectively, upon contacts 163, 164, and 165, these contacts being terminals of the line of substation A'.

As side switch wiper 157 comes into engagement with its third position contact point, a circuit is completed from ground at G¹¹ by way of wiper 161, bank contact 164, and winding of cut-off relay 20' to battery B. The cut-off relay 20', upon energizing, disconnects the line conductors of substation A' from their connections at the line relay 21'. Ground at G¹¹ also extends to multiples of contact 164 in the banks of other connectors of the group, thereby making the line of 20 substation A' busy to other calls.

By the engagement of side switch wipers 158 and 159 with their third position contact points the line conductors 11 and 12 are extended to the wipers 160 and 162, respectively, thereby completing the connection between the two substations. By the engagement of side switch wiper 156 with its third position contact point, a circuit is completed for the ringing relay 149 in series with the 30 interrupter I, whereby ringing current is projected intermittently out over the line of substation A' to signal the called subscriber.

The subscriber at substation A has now established the required connection with substation A' and the bell at the latter substation is being rung to attract the attention of the subscriber. When the subscriber at substation A' removes his receiver from the hook a circuit is completed for the double 40 wound answering bridge relay 150, which relay serves to supply talking battery to the transmitter at substation A'. Relay 150, upon energizing, completes a circuit for the ring cut off relay 148, which relay locks up 45 and breaks the circuit of the ringing relay 149, thereby stopping the ringing. As a further result of the energization of relay 150, the incoming line conductors are reversed as regards their connection with the 50 windings of line relay 140. This operation is without importance in the system shown herein, although it is provided in case it is desired to operate meters or similar apparatus.

55 The calling and the called subscriber may now converse without further effort, the voice currents taking the path shown by the heavy lines.

Upon the completion of the conversation 60 the subscribers will hang up their receivers. By the replacement of the receiver at substation A the circuit of line relay 140 is broken. Upon deenergizing relay 140 breaks the circuit of slow acting relay 153. Upon 65 the deenergization of relay 153, the connec-

tor E is restored to normal in the regular manner and as a further result, ground is removed from the holding circuit extending back to selector D and finder switch C. The selector D is then restored to normal following the deenergization of relay 107, and line switching relay 51 of the finder switch C, line relay 21, and cut off relay 20 are deenergized, whereupon all the apparatus will have been restored to normal position. It 70 should be mentioned that the line switching relay 51 is made slightly slow acting to insure that spring 63 will not make against contact 66 until after armature 31 of the line relay leaves spring 32. The reason for 75 this adjustment is obvious.

The operation of a connector such as the connector E when the called line is busy is well known and has been fully described in the publications referred to. My invention 80 involves nothing new in connection with this feature, consequently it is thought to be unnecessary to describe such operation here.

Referring now to Fig. 5, I will describe the operation of the relays shown at H which 85 relays may be termed emergency starting and stopping relays. As implied above these relays perform no useful function in the ordinary operation of the system but are provided to care for extraordinary 90 conditions. The relays 90 and 91 are of rather low resistance and are in series, respectively, with a common locking wire extending to all the line relays of the group of lines, and a common battery supply wire extending to 100 the rotary magnets of all the finder switches of the group. The relays 92 and 93 are normally energized and are controlled, respectively by the relays 91 and 90.

From the previous description of the 105 operation of finder switch C, it will be clear that the line relay of a calling line is locked up by way of common locking conductor and relay 90 during the time a finder switch is rotating to find that line. Since the rotary magnets of all the finder switches of the group are in series with relay 91, it follows that in the ordinary operation of the system whenever relay 90 is energized relay 91 will be energized also.

110 Assume now that two subscribers whose starting wires happen to be tapped on to the same section of the starting loop remove their receivers at the same instant. It is evident that but one finder switch will be 115 started. This finder will stop at whichever line it reaches first, whereupon relay 91 will deenergize, but relay 90 will remain energized since the second calling subscriber still has his line relay locked up. Relay 91, being slow acting, will pull up its armatures when the first impulse of current passes through it in series with the rotary magnet and retains its armatures until the finder 120 switch comes to rest on the contacts of the 125 130

calling line. The ungrounded pole of battery B' is now connected to conductor 95 by way of back contact of relay 93 and back contact of relay 91. Conductor 95 is joined 5 to the starting loop at some convenient point and affords means for starting another finder switch to locate the second calling line.

We will assume now that a subscriber 10 moves his receiver and thereby starts a finder switch hunting for his line; but before the finder switch reaches his line, the receiver is replaced. By the replacement 15 of the receiver the line relay of the calling line is deenergized and battery potential from the cut-off relay is removed from the multiple test contacts of that line in the finder switch banks. When, therefore, the finder which was started arrives at the contacts of the line in question, its test wiper finds no battery potential and the finder switch is unable to stop, but will continue 20 to rotate indefinitely. I provide, however, a conductor indicated by reference character 25 96 which at this time will have battery potential upon it by way of back contacts of relays 90 and 92. Conductor 96 is joined to one or more multiple test contacts in the 30 finder banks and affords means for stopping a rotating finder switch when there is no calling line waiting to be served.

It will be seen from the foregoing that I have provided a very efficient method of 35 starting finder switches in a system of the general type described, by which the movement of the finders is reduced to a minimum; and it will be seen further that I have provided certain new and advantageous circuit arrangements for accomplishing the 40 foregoing and other beneficial results, thereby by tending to increase the general serviceability of a finder switch system.

While I have described in the foregoing 45 certain specific embodiments of my invention, I do not wish to be held strictly to the forms shown herein, for various adaptations will no doubt suggest themselves to persons skilled in the art. I desire, therefore, to include and have protected by Letters Patent 50 all forms and modifications of my invention which may come within the scope of the appended claims.

What I claim as my invention is:

1. In a telephone system, a group of lines, 55 link circuits each comprising a pair of talking conductors, a finder switch for each link for connecting a calling line of said group thereto, and a pair of normally closed contact members in each of said finder switches individual to each of said lines.

2. In a telephone system, a group of lines, 60 trunk lines, finder switches and selector switches connected in pairs for extending a calling line of said group to an idle one of said trunk lines, and a pair of normally

closed contact members in each of said finder switches individual to each of said first mentioned lines.

3. In a telephone system, a group of lines, link circuits, a finder switch for each 70 link for connecting a calling line of said group thereto, a pair of normally closed contact members in each of said finder switches individual to each of said lines, and a circuit including all of said contact members in series.

4. In a telephone system, a group of lines, trunk lines, finder switches and selector switches connected in pairs for extending a calling line of said group to an idle one of 80 said trunk lines, a pair of normally closed contact members in each of said finder switches individual to each of said first mentioned lines, and a circuit including all of said contact members in series. 85

5. In a telephone system, a group of lines, link circuits, a finder switch for each link for connecting a calling line of said group thereto, a pair of normally closed contact members in each of said finder switches individual to each of said lines, a circuit including all of said contact members in series, and an insulating member associated with each of said finder switches for separating the contact members of one of said 90 pairs. 95

6. In a telephone system, a group of lines, trunk lines, finder switches and selector switches connected in pairs for extending a calling line of said group to an idle one of 100 said trunk lines, a pair of normally closed contact members in each of said finder switches individual to each of said first mentioned lines, a circuit including all of said contact members in series, and an insulating member associated with each of said 105 finder switches for separating the contact members of one of said pairs.

7. In a telephone system, a group of lines, link circuits, a finder switch for each link for 110 connecting a calling line of said group thereto, a pair of normally closed contact members in each of said finder switches individual to each of said lines, a circuit including all of said contact members in series, and an insulating member associated with each of 115 said finder switches for separating the contact members of one of said pairs, whereby the said circuit may be divided into sections.

8. In a telephone system, a group of lines, trunk lines, finder switches and selector switches connected in pairs for extending a calling line of said group to an idle one of 120 said trunk lines, a pair of normally closed contact members in each of said finder switches individual to each of said first mentioned lines, a circuit including all of said contact members in series, and an insulating member associated with each of said 125 finder switches for separating the contact members 130

of one of said pairs, whereby the said circuit may be divided into sections.

9. In a telephone system, a group of lines, link circuits, a finder switch for each link for connecting a calling line of said group thereto, a pair of normally closed contact members in each of said finder switches individual to each of said lines, a circuit including all of said contact members in series, 5 an insulating member associated with each of said finder switches for separating the contact members of one of said pairs, whereby the said circuit may be divided into sections, a controlling relay in each of said 10 finder switches, and means for connecting each of said relays to one of said sections.

10. In a telephone system, a group of lines, trunk lines, finder switches and selector switches connected in pairs for extending a calling line of said group to an idle one of said trunk lines, a pair of normally closed contact members in each of said finder switches individual to each of said first mentioned lines, a circuit including all of said 20 contact members in series, an insulating member associated with each of said finder switches for separating the contact members of one of said pairs, whereby the said circuit may be divided into sections, a controlling 25 relay in each of said finder switches, and means for connecting each of said relays to one of said sections.

11. In a telephone system, a group of lines, link circuits, a finder switch for each link for connecting a calling line of said group thereto, a pair of normally closed contact members in each of said finder switches individual to each of said lines, a circuit including all of said contact members in series, and a branch of said circuit for each of said lines.

12. In a telephone system, a group of lines, trunk lines, finder switches and selector switches connected in pairs for extending a calling line of said group to an idle one of said trunk lines, a pair of normally closed contact members in each of said finder switches individual to each of said first lines, a circuit including all of said contact members in series, and a branch of said circuit for each of said first lines.

13. In a telephone system, a group of lines, link circuits, a finder switch for each link for connecting a calling line of said group thereto, a pair of normally closed contact members in each of said finder switches individual to each of said lines, a circuit including all of said contact members in series, a branch of said circuit for each of said lines, and a relay individual to each of said lines for disconnecting its associated branch.

14. In a telephone system, a group of lines, trunk lines, finder switches and selector switches connected in pairs for extending a calling line of said group to an idle one of said trunk lines, and a starting relay in each

ing a calling line of said group to an idle one of said trunk lines, a pair of normally closed contact members in each of said finder switches individual to each of said first lines, a circuit including all of said contact members in series, a branch of said circuit for each of said first lines, and a relay individual to each of said first lines for disconnecting its associated branch.

15. In a telephone system, a group of lines, link circuits, a finder switch for each link for connecting a calling line of said group thereto, a pair of normally closed contact members in each of said finder switches individual to each of said lines, and a circuit including all of said contact members in series, each of said lines when idle having one of its conductors conductively connected to said circuit.

16. In a telephone system, a group of lines, trunk lines, finder switches and selector switches connected in pairs for extending a calling line of said group to an idle one of said trunk lines, a pair of normally closed contact members in each of said finder switches individual to each of said first lines, and a circuit including all of said contact members in series, each of said lines when idle having one of its conductors conductively connected to said circuit.

17. In a telephone system, a group of lines, link circuits, a finder switch for each link for connecting a calling line of said group thereto, and a starting relay in each of said finder switches, each starting relay being controllable, when its associated finder switch is idle, either from any line in said group, or from only one of said lines, or from any intervening number of lines in said group.

18. In a telephone system, a group of lines, trunk lines, finder switches and selector switches connected in pairs for extending a calling line of said group to an idle one of said trunk lines, and a starting relay in each of said finder switches, each starting relay being controllable, when its associated finder switch is idle, either from any line in said group, or from only one of said lines, or from any intervening number of lines in said group.

19. In a telephone system, a group of lines, link circuits, a finder switch for each link for connecting a calling line of said group thereto, and a starting relay in each of said finder switches, each starting relay being controllable, when its associated finder switch is idle, either from any line in said group, or from only one of said lines, or from any intervening number of lines in said group.

20. In a telephone system, a group of lines, trunk lines, finder switches and selector switches connected in pairs for extending a calling line of said group to an idle one of said trunk lines, and a starting relay in each

of said finder switches, each starting relay being controllable, when its associated finder switch is idle, either from any line in said group, or from only one of said lines, or 5 from any intervening number of lines in said group.

21. In a telephone system, a group of lines, link circuits, a finder switch for each link for connecting a calling line of said group 10 thereto, a pair of normally closed contact members in each of said finder switches individual to each of said lines, an insulating member associated with each of said finder switches for separating the contact members 15 of one of said pairs, means for rotating each of said insulating members during the operation of its associated finder switch, and means for connecting the two contact members of a pair when separated by the insulating member of a busy finder switch. 20

22. In a telephone system, a group of lines, trunk lines, finder switches and selector switches connected in pairs for extending a calling line of said group to an idle one of 25 said trunk lines, a pair of normally closed contact members in each of said finder switches individual to each of said first lines, an insulating member associated with each of said finder switches for separating the contact members 30 of one of said pairs, means for rotating each of said insulating members during the operation of its associated finder switch, and means for connecting the two contact members of a pair when separated by the insulating member of a busy 35 finder switch.

23. In a telephone system, a group of lines, link circuits, a finder switch for each link for connecting a calling line of said group 40 thereto, a pair of normally closed contact members in each of said finder switches individual to each of said lines, a circuit including all of said contact members in series, an insulating member associated with each of said finder switches for separating the contact members 45 of one of said pairs, whereby the said circuit may be divided into sections, and means for rotating each of said insulating members during the operation of its associated finder switch to vary the length of said sections. 50

24. In a telephone system, a group of lines, trunk lines, finder switches and selector switches connected in pairs for extending 55 a calling line of said group to an idle one of said trunk lines, a pair of normally closed contact members in each of said finder switches individual to each of said first lines, a circuit including all of said contact members in series, an insulating member associated with each of said finder switches for separating the contact members 60 of one of said pairs, whereby the said circuit may be divided into sections, and means for rotating each of said insulating members during the 65

operation of its associated finder switch to vary the length of said sections.

25. In a telephone system, a group of lines, link circuits, a finder switch for each link for connecting a calling line of said group 70 thereto, a pair of normally closed contact members in each of said finder switches individual to each of said lines, a circuit including all of said contact members in series, an insulating member associated with each 75 of said finder switches for separating the contact members of one of said pairs whereby the said circuit may be divided into sections, and means for connecting the two contact members of a pair when separated by the insulating member of a busy finder switch, whereby the number of said sections is made equal to the number of idle finder switches.

26. In a telephone system, a group of 85 lines, trunk lines, finder switches and selector switches connected in pairs for extending a calling line of said group to an idle one of said trunk lines, a pair of normally closed contact members in each of said finder 90 switches individual to each of said first lines, a circuit including all of said contact members in series, an insulating member associated with each of said finder switches for separating the contact members of one of 95 said pairs, whereby the said circuit may be divided into sections, and means for connecting the two contact members of a pair when separated by the insulating member of a busy finder switch, whereby the number of 100 said sections is made equal to the number of idle finder switches.

27. In a telephone system, a group of lines, a telephone for each line, a lesser group of automatic switches, a controlling 105 circuit for said switches including a pair of normally closed contact members individual to each of said lines, and means associated with said switches for establishing a talking circuit between any two of said lines. 110

28. In a telephone system, a group of lines, a lesser group of automatic switches, a controlling circuit including a pair of normally closed contact members individual to each of said lines in each of said switches, 115 and means associated with said controlling circuit for starting said switches one at a time.

29. In a telephone system, a group of lines, a lesser group of automatic switches 120 for extending said lines when calling, a controlling circuit including a pair of normally closed contact members individual to each of said lines in each of said switches, and means associated with said controlling circuit responsive to successive calls for starting said switches in succession. 125

30. In a telephone system, a group of lines, a lesser group of automatic switches, a controlling circuit including a pair of nor- 130

5 mally closed contact members individual to each of said lines in each of said switches, means associated with each of said switches for separating the contact members of one 5 of said pairs, whereby the said controlling circuit may be divided into sections.

31. In a telephone system, a group of lines, a lesser group of automatic switches, a controlling circuit including a pair of normally closed contact members individual to each of said lines in each of said switches, and means associated with each of said switches for separating the contact members of one of said pairs, whereby the said controlling circuit may be divided into sections equal in number to the number of said switches.

32. In a telephone system, a group of lines, a lesser group of automatic switches, a controlling circuit including a pair of normally closed contact members individual to each of said lines in each of said switches, means associated with each of said switches for separating the contact members of one 25 of said pairs, whereby the said controlling circuit may be divided into sections equal in number to the number of said switches, and means included in each of said switches for connecting the members separated by said 30 first means when the associated switch is busy, whereby the number of sections is made equal to the number of idle switches.

33. In a telephone system, a group of lines, a lesser group of automatic switches, a controlling circuit including a pair of normally closed contact members individual to each of said lines in each of said switches, means associated with each of said switches for separating the contact members of one 40 of said pairs whereby the said controlling circuit may be divided into sections equal in number to the number of said switches, a controlling relay for each of said switches, and means for connecting each relay to one 45 of said sections.

34. In a telephone system, a group of lines, a lesser group of automatic switches, for extending said lines when calling, and means for starting said switches in succession responsive to successive calls comprising a controlling circuit including a pair of normally closed contact members individual to each of said lines, and a branch of said controlling circuit for each of said lines.

35. In a telephone system, a group of lines, a lesser group of automatic switches, for extending said lines when calling, and means for starting said switches in succession responsive to successive calls comprising a controlling circuit including a pair of normally closed contact members individual to each of said lines in each of said switches, and a branch of said controlling circuit for each of said lines.

36. In a telephone system, a group of

lines, a lesser group of automatic switches, a controlling circuit including a pair of normally closed contact members individual to each of said lines, a branch of said controlling circuit extending over each of said lines, and means for disconnecting each of said branches from its associated line when the line is busy.

37. In a telephone system, a group of lines, a lesser group of automatic switches, a controlling circuit comprising a continuous loop and including a pair of normally closed contact members individual to each of said lines in each of said switches, a branch of said controlling circuit for each of said lines, and means for disconnecting each of said branches when its associated line is busy.

38. In a telephone system, a line, an automatic switch, a finder switch operable for extending said line to said automatic switch, a controlling relay for said finder switch, a line relay for said line having a main and an auxiliary winding, a circuit including said controlling relay and the main winding of said line relay, and means controlled by said line relay for interrupting said circuit.

39. In a telephone system, a line, an automatic switch, a finder switch operable for extending said line to said automatic switch, a controlling relay for said finder switch, a line relay for said line having a main and an auxiliary winding, a circuit including said controlling relay and the main winding of said line relay, and means controlled by said line relay for interrupting said circuit and for completing it over a path excluding said controlling relay.

40. In a telephone system, a line, an automatic switch, a finder switch operable for extending said line to said automatic switch, a controlling relay for said finder switch, a line relay for said line having a main and an auxiliary winding, a circuit including said controlling relay and the main winding of said line relay, means controlled by said line relay for interrupting said circuit and for completing it over a new path excluding said controlling relay, and a second circuit for said line relay by way of its auxiliary winding.

41. In a telephone system, a line, an automatic switch, a finder switch operable for extending said line to said automatic switch, a controlling relay for said finder switch, a line relay for said line having a main and an auxiliary winding, a circuit including said controlling relay and the main winding of said line relay, means controlled by said line relay for interrupting said circuit, a second relay for said line, and a second circuit including said second relay and said auxiliary winding.

42. In a telephone system, a line, an automatic switch, a finder switch operable for

extending said line to said automatic switch, a controlling relay for said finder switch, a line relay for said line having a main and an auxiliary winding, a circuit including said controlling relay and the main winding of said line relay, means controlled by said line relay for interrupting said circuit, a cut-off relay for said line, and a test circuit including said cut-off relay and said auxiliary winding.

43. In a telephone system, a line, an automatic switch, a finder switch operable for extending said line to said automatic switch, a controlling relay for said finder switch, a line relay for said line having a main and an auxiliary winding, a circuit including said controlling relay and the main winding of said line relay, means controlled by said line relay for interrupting said circuit and for completing it over a path excluding said controlling relay, a cut-off relay for said line, and a test circuit including said cut-off relay and said auxiliary winding.

44. In a telephone system, a line, an automatic switch, a finder switch for extending said line to said automatic switch, a line relay for said line having two windings, a controlling relay for said finder switch, a circuit for initiating the operation of said finder switch including said controlling relay and one winding of said line relay, and a circuit for stopping the operation of said finder switch including said controlling relay and the other winding of said line relay.

45. In a telephone system, a line, an automatic switch, a finder switch for extending said line to said automatic switch, a line relay for said line having two windings, a pair of controlling relays for said finder switch, a circuit for initiating the operation of said finder switch including said controlling relays and one winding of said line relay, and a circuit for stopping the operation of said finder switch including one of said controlling relays and the other winding of said line relay.

46. In a telephone system, a line, an automatic switch, a finder switch for extending said line to said automatic switch, a controlling relay in said finder switch, a line relay for said line, and a circuit for initiating the operation of said finder switch, said circuit including said line and said relays.

47. In a telephone system, a line, an automatic switch, a finder switch for extending said line to said automatic switch, a pair of controlling relays in said finder switch having different time constants, a line relay for said line, and a circuit for initiating the operation of said finder switch, said circuit including said line and said relays.

48. In a telephone system, a line, an automatic switch, a finder switch for extending said line to said automatic switch, a controlling relay in said finder switch, a line re-

lay for said line, a circuit for initiating the operation of said finder switch, said circuit including said line and said relays, and means under the control of said line relay for interrupting said circuit.

49. In a telephone system, a line, an automatic switch, a finder switch for extending said line to said automatic switch, a pair of controlling relays in said finder switch having different time constants, a line relay for said line, a circuit for initiating the operation of said finder switch, said circuit including said relays, and means under the control of said line relay for interrupting said circuit.

50. In a telephone system, a line, an automatic switch, a finder switch for extending said line to said automatic switch, a controlling relay in said finder switch, a line relay for said line, a circuit for initiating the operation of said finder switch, said circuit including said line and said relays, and means under the control of said line relay for interrupting said circuit, and for completing said circuit over a different path to the exclusion of said controlling relay.

51. In a telephone system, a line, an automatic switch, a finder switch for extending said line to said automatic switch, a pair of controlling relays in said finder switch having different time constants, a line relay for said line, a circuit for initiating the operation of said finder switch, said circuit including said line and said relays, and means under the control of said line relay for interrupting said circuit and for completing said circuit over a different path to the exclusion of said controlling relays.

52. In a telephone system, a group of lines, a lesser group of automatic switches, finder switches for extending a calling line of said group to an idle one of said automatic switches, a relay common to said lines, a relay common to said finder switches, and a circuit for initiating the operation of one of said finder switches controlled jointly by said relays.

53. In a telephone system, a group of lines, a lesser group of automatic switches, finder switches for extending a calling line of said group to an idle one of said automatic switches, a relay common to said lines, a relay common to said finder switches, and a circuit controlled jointly by said relays for bringing an operating one of said finder switches to rest.

54. In a telephone system, a group of lines, automatic switches, finder switches less in number than the lines for extending a calling line of said group to an idle one of said automatic switches, and means under the control of said calling line for operating and releasing the selected auto-

- matic switch without altering the connective position of its associated finder switch.
55. In a telephone system, a group of lines, automatic switches, a finder switch for each of said automatic switches, fixed terminals for said lines, movable terminals for said finder switches, each of said movable terminals in engagement at all times with some one of said fixed terminals, and 10 means whereby a calling line, having its fixed terminal already engaged by a movable terminal, may be extended thereby into connection with one of said automatic switches.
56. In a telephone system, the combination, with a plurality of lines and fixed multiple terminals therefor, of a plurality of movable terminals each of which is at all times in engagement with one of said 20 fixed terminals, and means under the control of a calling line for advancing the nearest idle movable terminal into engagement with the fixed terminal of the said calling line.
57. In combination, a plurality of telephone lines, a lesser plurality of automatic switches, fixed multiple terminals for said lines associated with each of said switches, a movable terminal for each of 30 said switches in engagement with one of its associated multiple terminals, and means whereby a calling line having its multiple terminals unengaged may initiate the operation of that switch whose movable terminal requires the least movement to engage the multiple terminal of the said calling line.
58. In combination, a plurality of telephone lines, a lesser plurality of automatic 40 switches, fixed multiple terminals for said lines associated with each of said switches, a movable terminal for each of said switches in engagement with one of its associated multiple terminals, and means whereby a calling line having its multiple terminals unengaged may initiate the operation of that switch whose movable terminal requires the least movement to engage the multiple terminals of the said calling line, said means comprising a controlling circuit for said last 50 switch including one of the conductors of said line.
59. In combination, a plurality of telephone lines, a lesser plurality of automatic 55 switches, fixed multiple terminals for said lines associated with each of said switches, a movable terminal for each of said switches in engagement with one of its associated multiple terminals, and means whereby a calling line having its multiple terminals unengaged may initiate the operation of that switch whose movable terminal requires the least movement to engage the multiple terminals of the said calling line, said means comprising a controlling circuit for said last 60
- switch having a branch for each of a plurality of said lines.
60. In a telephone system, a group of lines, a group of automatic switches for extending said lines when calling, a controlling circuit 70 forming a continuous loop and including a pair of normally closed contact members individual to each of said lines in each of said switches, and a branch of said controlling circuit for each of said lines. 75
61. In a telephone system, a group of lines, a group of finder switches, a pair of normally closed contact members individual to each of said lines in each of said switches, a circuit connecting all of said contact pairs in 80 series to form a continuous loop and a starting wire for each line connected to said circuit.
62. In a telephone system, a group of lines, a group of finder switches, a pair of normally closed contact members individual to each of said lines in each of said switches, a circuit connecting all of said contact pairs in 85 series to form a continuous loop, and starting wires associated with the said lines and switches, respectively, in electrical connection with said circuit.
63. In a telephone system, a group of lines, a group of finder switches for extending said lines when calling, and means for starting 95 said switches in succession responsive to successive calls including a circuit extending a plurality of times through all of said switches in series.
64. In a telephone system, a group of lines, 100 a finder switch for extending said lines when calling, quick and slow relays in said switch, and a starting circuit including said relays connected in series.
65. In a telephone system, a group of lines, 105 a group of finder switches for extending said lines when calling, said finders having no normal position, and means responsive to a call for starting that one of said finders which requires the least movement to locate 110 the calling line.
66. In a telephone system, a group of lines, a group of finder switches for extending said lines when calling, said finders having no normal position, and means responsive to a 115 call for starting that one of said finders which requires the least movement to locate the calling line, said means comprising a starting circuit extending through all of said finder switches in series. 120
67. In a telephone system, a group of lines, a group of finder switches, fixed contacts for said lines multiplied in said switches, movable contacts for said switches for engaging said fixed contacts, the said movable contacts 125 having no normal position as regards the lines, and means responsive to a call for starting that one of said switches which requires the least movement of its movable contacts to locate the calling line. 130

68. In a telephone system, a group of telephone lines, a group of trunking switches, a group of finder switches for selecting calling lines and extending them to idle trunking switches, said finder switches having no normal position as regards the said lines, and the said finders constituting means whereby any calling line which has been so extended and which has a finder associated with it will be again extended by such finder without selective movement thereof.

69. In a telephone system, a group of telephone lines, trunk lines, a group of finder switches for selecting calling lines and extending them to said trunk lines, each finder switch being normally associated with the last selected line, and the said finder switches constituting means whereby any calling line already selected will be again extended by the associated finder switch without selective movement thereof.

70. In a telephone system, a group of lines, an automatic trunking switch, a finder switch for selecting a calling line and extending it to said trunking switch, and means for controlling said trunking switch over the calling line to operate and release the same while maintaining said finder switch in selective position as regards the said calling line.

71. In a telephone system, subscribers' lines, automatic trunking switches controllable over calling lines for extending connections to called lines, finder switches for selecting calling lines and extending them to idle trunking switches, and means for releasing established connections, the said finder switches, after the connections are released, remaining in association with the previously selected lines.

72. In a telephone system, a group of finder switches having movable terminals, a group of lines and multiple terminals therefor in said finder switches, and a starting circuit for each finder switch including a movable terminal thereof and a fixed terminal individual to one of said lines.

73. In a telephone system, a group of lines, a group of finder switches for extending said lines when calling, fixed contacts for each line in each finder switch and movable contacts for engaging the same in each finder switch, and a circuit for starting an idle finder switch responsive to a call, the said circuit including a movable contact of the finder switch to be started and a fixed contact engaged thereby individual to one of said lines.

74. In a telephone system, a group of lines, a group of finder switches for extending said lines when calling, means for starting an idle finder responsive to a call, and means for starting a second idle finder responsive to a subsequent call from any line in said group before the finder switch first

started has stopped, said means comprising a plurality of starting wires, means for establishing momentary starting circuits over said wires, and means for connecting two starting wires together whenever any finder is started.

75. In a telephone system, a group of lines, a group of finder switches for extending said lines when calling, and means for starting said finders in quick succession responsive to successive calls from any of the lines in said group, whereby two or more finders may be in operation simultaneously, said means comprising a plurality of starting wires, means for establishing momentary starting circuits over said wires, and means for connecting two starting wires together whenever any finder is started.

76. In a telephone system, a group of lines, a group of finder switches for extending said lines when calling, starting relays in said finders each subject to the control of a variable number of said lines, and circuit connections whereby the operation of one finder responsive to a call will vary the number of lines to which the starting relay of another finder is subject to control to an extent proportionate to the movement of the operated finder.

77. In a telephone system, a group of lines, a group of finder switches for extending said lines when calling, starting relays in said finders each subject to the control of a variable number of said lines, and circuit connections such that the operation and restoration to idle condition of one finder responsive to a call may increase and decrease, respectively, the number of lines to which the starting relay of another finder is subject to control, the amount of decrease being different from the amount of increase.

78. In a telephone exchange system, a plurality of calling substation lines arranged in groups, a plurality of finder switches serving said lines, there being a finder switch normally assigned to each of said groups, and means for causing a plurality of finders to search simultaneously for lines calling in the same group at the same time, said means comprising an incoming and outgoing starter wire at each finder, and contacts at each finder effective while the finder is in motion for connecting the associated starter wires.

79. In a telephone exchange system, a plurality of calling substation lines arranged in groups, a plurality of finder switches serving said lines, there being one of said finder switches normally assigned to each of said groups, a starter wire circuit to control the starting of the switch of a succeeding group when the switch normally assigned to the group in which the call originates is busy, contacts for extending said

5 starter wire to a succeeding switch when a calling line is seized, and other contacts for bridging said first named contacts to start a succeeding switch without awaiting the closure of said first named contacts in case a second call is originated in the same group before the first calling line is seized.

80. In a telephone system, a group of lines, a group of finder switches, means 10 dividing said lines into sub-groups, there being a finder normally assigned to each sub-group, means including a starter wire whereby a calling line in one of said sub-groups can start the finder assigned to such sub-group, and means effective when such finder is started for extending the said starter wire to the finder assigned to the next sub-group, whereby another calling line in the same sub-group with the first 15 calling line can start another finder before the finder first started has stopped.

81. In a telephone system, a plurality of subscribers' lines, a lesser plurality of single motion finder switches, means whereby 20 any calling line can start one of said finders, grouping means whereby separate pluralities of lines are normally adapted to start different finders, and means whereby a plurality of calling lines which are 25 normally assigned to the same finder can start a plurality of finders and cause said finders to operate simultaneously.

82. In a telephone system, a plurality of finder switches, a plurality of lines normally divided into groups for the purpose 30 of starting said finders, there being a finder assigned to each group of lines, means whereby a calling line in one of said groups can start the finder assigned to such group, 35 and means responsive to the starting of such finder for combining the associated group with the next succeeding group, whereby another calling line in the same group can start another finder while the 40 first started finder is searching for the first calling line.

83. In a telephone system, a plurality of subscribers' lines divided into groups, a lesser plurality of finder switches, there 45 being a finder switch normally assigned to each of said groups, and means for starting a plurality of finders and operating the same simultaneously in search of lines calling in the same group at the same time, said means including a starter wire terminating 50 in each finder, and contacts for connecting two starter wires together as soon as a finder is started.

84. In a telephone system, a line, a trunk 60 line, a finder switch for connecting said line and trunk line, a line relay energized over said line for starting said finder, a cut-off relay for disconnecting said line relay, a holding winding on said line relay,

and a circuit for said cut-off relay completed by said finder when the line and trunk are connected, said circuit including the holding winding of said line relay.

85. In a telephone system, a line, a trunk line, a finder switch for connecting said line and trunk line, a test wiper for said finder, a test contact individual to said line, a line relay energized over said line to start said finder, said line relay also effective to change the potential on said test contact to enable the finder to find the line, a cut-off relay for disconnecting said line relay, a holding winding for said line relay, and a circuit established after the line is found including said cut-off relay, said holding winding, and the said test contact and wiper.

86. In a telephone system, a subscriber's line, line and cut-off relays individual to said line, an automatic switch for extending said line when calling, circuits for energizing said line relay over the line to start said switch when the call is initiated, for energizing the cut-off relay after the switch has operated, and for maintaining the line relay energized independent of the line, a second switch for completing connections to said line as a called line, and a circuit completed when the line is called for energizing said cut-off relay while said line relay remains deenergized.

87. In a telephone system, a subscriber's line, line and cut-off relays individual to said line, automatic switches for extending calls to or from said line, a circuit for energizing the cut-off relay alone when an incoming call is extended to said line, a circuit for energizing the line relay alone when an outgoing call is initiated, means for breaking said circuit before the connection is completed, and a circuit for energizing the cut-off relay and for maintaining the line relay energized thereafter until the connection is released.

88. In a telephone system, a subscriber's line, a selector switch, a finder switch for connecting said line with said selector, a trunk line connecting the finder and selector and including a release trunk conductor, means for grounding said conductor at the selector, a wiper switching relay in said finder, line and cut-off relays individual to said line, and circuit connections by which all of said relays are maintained energized over said release trunk conductor.

89. In a telephone system, a group of lines, a finder switch for extending said lines when calling, a starting relay and a motor magnet in said switch, means responsive to a call for energizing and deenergizing said relay, a second relay in circuit with said first relay and having a slow to release characteristic, and a circuit for said motor

magnet completed while the first relay is deenergized and the second relay is energized.

90. In a telephone system, a group of 5 lines, a finder switch for extending said lines when calling, a starting relay and a motor magnet in said switch, means responsive to a call for energizing and deenergizing said relay, and a circuit for said motor magnet completed when said relay is deenergized.

91. In a telephone system, a finder switch for extending a subscriber's line when calling, a combination starting and stopping 15 relay in said switch, means for energizing and deenergizing said relay to start said finder searching for said line, and means for again energizing said relay to stop said finder when the line is found.

92. In a telephone system, a group of 20 lines, a finder switch for extending said lines when calling, wipers in said finder always in engagement with some one of said lines, a starting relay in said finder and a circuit for energizing it momentarily 25 responsive to a call, and a locking circuit for maintaining the starting relay energized in case the line engaged by the finder wipers is the line which is calling.

93. In a telephone system, a group of 30 lines, a finder switch for extending said lines when calling, wipers in said finder always

in engagement with some one of said lines, a starting relay in said finder, a circuit for energizing said relay responsive to a call, 35 the relay being deenergized to start the finder in case its wipers are not in engagement with the calling line, a locking circuit for temporarily holding said relay energized in case the finder wipers are already 40 in engagement with the calling line, and a wiper switching relay operated responsive to the continued energization of said starting relay.

94. In a telephone system, a finder switch 45 for extending a subscriber's line when calling, a motor magnet in said finder, means for transmitting a starting impulse to said magnet, and a slow acting relay in series with said magnet for maintaining its circuit closed until the line is found.

95. In a telephone system, a finder switch 55 for extending a subscriber's line when calling, a motor magnet in said finder, means for transmitting a starting impulse to said magnet, a slow acting relay in circuit with said motor magnet for holding its circuit closed while the finder is searching for the line, and a second relay for opening said circuit to stop the switch when the line is 60 found.

Signed by me at Chicago, Ill., this 10th day of February, 1916.

RODNEY G. RICHARDSON.
